US00D843210S

(12) **United States Design Patent** (10) Patent No.: **US D843,210 S**
(45) Date of Patent: **** Mar. 19, 2019**

(54) **MIXING CONTAINER LID**

- (71) Applicant: **Adam Friedman**, Gainesville, VA (US)
(72) Inventor: **Adam Friedman**, Gainesville, VA (US)
(**) Term: **15 Years**
(21) Appl. No.: **29/534,872**
(22) Filed: **Jul. 31, 2015**

(57) **CLAIM**

The ornamental design for a mixing container lid, as shown and described.

DESCRIPTION

FIG. 1 is a top, front and right side perspective view of a mixing container lid showing my new design.

FIG. 2 is a bottom, rear and left side perspective view thereof.

FIG. 3 is a top view thereof.

FIG. 4 is a bottom view thereof.

FIG. 5 is a left side view thereof.

FIG. 6 is a right side view thereof.

FIG. 7 is a rear view thereof.

FIG. 8 is a front view thereof.

FIG. 9 is an exploded top, rear and right side perspective view thereof, shown in an alternate condition of use; and, FIG. 10 is an assembled top perspective view thereof.

The broken lines are shown for the purposes of illustrating environmental subject matter that forms no part of the claim.

1 Claim, 10 Drawing Sheets
